CLAIM

The ornamental design for a protector for cooking pans, as shown and described.

DESCRIPTION

FIG. 1 shows a first perspective view of a protector for cooking pans.

FIG. 2 shows a second perspective view of the protector for cooking pans of FIG. 1.

FIG. 3 shows a view of a first side of the protector for cooking pans of FIG. 1.

FIG. 4 shows a view of a second side, opposite to the first side of FIG. 3, of the protector for cooking pans of FIG. 1. FIG. 5 shows a view of a third side, between the first side of FIG. 3 and the second side of FIG. 4, of the protector for cooking pans of FIG. 1.

FIG. 6 shows a view of a fourth side, opposite to the third side of FIG. 5, of the protector for cooking pans of FIG. 1. FIG. 7 shows a top plan view of the protector for cooking pans of FIG. 1; and,

FIG. 8 shows a bottom plan view of the protector for cooking pans of FIG. 1.

The shading and contour lines, having periodic breaks, in FIGS. 1–8 represent shading and contour and not surface ornamentation. The dashed lines in FIGS. 1–8 form no part of the claimed invention. The dash-dot-dash lines in FIGS. 1–8 depict a boundary of the claim and form no part thereof.

1 Claim, 8 Drawing Sheets
